UNITED STATES PATENT OFFICE.

BRUNO G. POHLMANN, OF SIEMENSSTADT, NEAR BERLIN, GERMANY, ASSIGNOR TO SIEMENS & HALSKE AKTIENGESELLSCHAFT, OF SIEMENSSTADT, NEAR BERLIN, GERMANY, A CORPORATION OF GERMANY.

TRANSMISSION SYSTEM.

Application filed May 29, 1926, Serial No. 112,419, and in Germany May 14, 1925.

This invention relates to electrical transmission systems and has for its general object to compensate for the distortion produced by a long transmission line.

As is well known, the distortion of long telephone lines is eliminated either by using repeaters having amplification characteristics proportioned to compensate for the line distortion or by inserting correcting artificial lines having attenuation characteristics complementary to the attenuation of the line in combination with repeaters having substantially flat amplification characteristics. In both cases an overall characteristic which is independent of frequency is desired. Generally the line is divided into sections and the distortion in each section is corrected by the corresponding repeater or the equalizer associated therewith. In long transmission lines, which necessarily embrace a large number of repeater sections, the demands made on the precision of correction at each individual repeater point are exceedingly high since any deviations from the attenuation or amplification characteristic required, which may be produced by slight inaccuracies in the correcting means, likely occur at each repeater in the same frequency regions and consequently are cumulative for the entire transmission system.

A particular object of this invention is to overcome this difficulty.

Therefore, in accordance with one feature of the invention the correcting means of the sections comprising the transmission system are made different, the differences being such that the sections are complementary to each other giving an overall transmission characteristic which is substantially independent of frequency.

In a preferred embodiment of the invention in a system comprising a large number of sections, each of a group of sections is corrected to give an approximately constant characteristic and there is associated with one section of the group an additional correcting means having such a characteristic as to compensate for the combined discrepancies of the group.

If the transmission system is of such length that it embodies several groups of sections of similar design the variations from the desired characteristic in each group may be cumulative in a similar manner as

the variations in the sections of each group so that it is desirable to provide additional means to compensate for the total group inaccuracies within the system in the same manner as the total section inaccuracies are compensated in each group. If the system is of such length that it is desirable to regroup the groups this method may be extended still further.

Since, from a design standpoint, it is desirable to keep the correcting means as unitary as possible, an attempt is made to adhere to this principle so far as possible without deviating from the spirit of the invention. Thus within a section, group, or system all sections or groups but one can be similarly constructed, their associated correcting means being so designed that an overall substantially constant characteristic is obtained. If correcting repeaters are employed the repeaters can either be particularly designed so that the amplification depends upon the frequency in a manner different from the standard repeaters, or else a repeater of the standard type having special associated correcting means can be used.

The spacing of the special repeater points is preferably so chosen that the net distortion over the portion of the line therebetween is of the same order of magnitude as is ordinarily corrected for with a single network. In this way a practically complete correction is obtained, even with very great lengths of line, without extraordinary demands being made upon the correcting means at the special repeater points.

A limiting case is the one in which the group consists of only two sections in which the errors of correction are so displaced with respect to each other that they practically neutralize one another. A transmission system of a large number of sections is then comprised of mere groups of two sections each so that altogether it is only necessary to construct two types of correcting means, except where with an extraordinarily large number of groups an elimination of systematic errors of correction is again necessary.

These and other objects, features and aspects of the invention can be more readily understood by reference to the following detailed description of one particular embodiment of the invention in connection with the drawing in which:

Fig. 1 shows graphically the attenuation and amplification characteristic of a single line section and repeater.

Fig. 2 shows graphically the net distortion in a group of corrected sections and

Fig. 3 shows diagrammatically one embodiment of a transmission system according to this invention.

Curve *b* of Fig. 1 shows the attenuation characteristic of a single repeater section plotted against frequency, while curve *s* of the same figure shows the amplification characteristic of a correcting repeater associated with the same section plotted against frequency. It will be noted that the deviations of the amplification curve from the attenuation curve are fairly small giving a characteristic for a single section which is approximately constant with frequency. Curve *b*_r of Fig. 2, however, shows the net equivalent curve for six repeater sections, the inaccuracies in the six sections having added up to give a characteristic which is sufficiently distorted to disturb speech transmission.

Fig. 3 shows a transmission system composed of six line sections 1, 2, 3, 4, 5 and 6 and associated repeaters, 11, 12, 13, 14, 15 and 16. Assuming that the attenuation in each section is represented by the curve *b* of Fig. 1, it has been found desirable for carrying out this invention to design the repeaters to have an amplification characteristic *s'* somewhat higher than *s* which would be required for compensating for the attenuation of a single section. This gives a total attenuation characteristic for the six sections as shown by the curve *b'*_r. Associated with the sixth repeater 16 is a network *e* composed of two tuned circuits *e*₁ and *e*₂ each designed to be resonant at one of the minima of the curve *b'*_r to give an overall characteristic as shown by the curve *b''* of Fig. 2 which is substantially independent of frequency. At the left of Fig. 3 is shown a second correcting network *e'* associated with the preceding group of repeater sections. Obviously instead of using tuned circuit other types of well known correcting networks may be employed in place thereof.

This invention is not limited to the par-

ticular embodiment shown but may be variously modified; for example, as described generally above. Similar arrangements may also be used for correcting for phase distortion or for both phase distortion and attenuation.

What is claimed is:

1. A transmission system comprising a line of a plurality of groups of sections, attenuation correcting means associated with each of a group of sections to give each of said sections similar transmission characteristics approximately independent of frequency and means associated with each group of sections to substantially compensate for the net variation of the total transmission characteristic of said group of sections from the desired constant frequency-transmission characteristic. 70

2. A transmission system comprising a multiplicity of tandem sections with amplifying repeaters connected between successive sections, means associated with certain repeaters at points along the system for correcting for unequal attenuation of different frequency components transmitted by the system, and means associated with repeaters at points respectively intermediate said certain repeaters proportioned with respect to the net attenuation of said system including the other repeaters and their associated correcting means, whereby substantially complete correction is made at a number of points along the system with points of approximate correction occurring therebetween. 80

3. The method of correcting for the unequal attenuation of the different frequency components transmitted by a line comprising a multiplicity of series sections, said method comprising making a substantially uniform approximate correction at each of a number of points along said line whereby the distortion is held within prescribed limits, and, at other points spaced along the line a plurality of sections apart, correcting for the net distortion resulting after the first-mentioned correcting steps. 95

In witness whereof, I hereunto subscribe my name this 28th day of April, A. D., 1926.

BRUNO G. POHLMANN.
